UNITED STATES PATENT OFFICE.

NOBLE ECKLES, OF SAN DIEGO, CALIFORNIA, ASSIGNOR OF THREE-FOURTHS TO LEWIS W. RHODE, OF LOS ANGELES, AND ONE-FOURTH TO CLAUS SPRECKELS, OF SAN DIEGO, CALIFORNIA.

CARBURETOR.

Application filed February 27, 1922. Serial No. 539,338.

This invention relates to carburetors. The primary aim of the invention is to provide a carburetor in which a hydro-carbon mixture is produced of correct proportions of air and fuel throughout the entire range of engine speeds with due regard to obtaining maximum economy; and in which the additional increments of fuel required for acceleration are automatically introduced at the proper time; so that without any manual adjustment, other than the throttle, the carburetor responds fully at all times in order to economically and efficiently handle the needs of the engine under varied conditions of load and speed.

The invention further aims to provide means for lifting fuel from a main tank or the like below the level of the carburetor, and to do this by the suction of the carburetor with a structure having a minimum of moving parts. Suction sufficient for this fuel lifting function is insured at substantially all engine speeds and all throttle positions by an anterior air inlet valve which is made responsive to the manifold suction posterior to the throttle.

In the more specific description following, reference will be made to the economizing function of one form of the device, whereby over-enriching of the mixture at certain speeds resulting in faulty operation, "loading," and the like, are effectively avoided. Over-enriching of the mixture is prevented or an economizing function is obtained by the aforesaid suction-operated valve in conjunction with an air conduit or orifice which controls fuel emission by air impact and air bleeding.

A more concrete understanding of my invention may be obtained from the following detailed description and the claims, taken in connection with the accompanying drawings in which:

Figure 1 is a longitudinal vertical section of a carburetor embodying the improvements of my invention,

Fig. 2 is a reduced transverse vertical section of the same taken on the line 2—2 of Fig. 1,

Fig. 3 is a fragmentary detail view of another arrangement,

Fig. 4 is a longitudinal vertical section of a modified construction,

Fig. 5 is a sectional view of the same

taken on the plane of the line 5—5 of Fig. 4, 55 and

Fig. 6 is a fragmentary plan view of the same.

Referring more particularly to the drawing, 10 designates a barrel-like mixing chamber having an air inlet 11 and a mixture outlet 12 in which is disposed a butterfly throttle valve 13 operably mounted on a shaft 14. A flange 15 is formed about the mixture outlet 12 for facilitating connection 65 of the carburetor to the intake manifold of an internal combustion engine (not shown).

The barrel or mixing chamber 10 is cast integrally with the constant level fuel supply chamber 16 in accordance with common 70 practice, this chamber having a float 17 pivoted at 18 and adapted to act upon a valve 19 for shutting off supply from the auxiliary tank 20 to be described presently.

A passageway 21 for fuel extends from 75 the constant level chamber 16 to the main nozzle, this main nozzle comprising a diametrical tubular portion 22 threaded at 23 to the barrel 10 and communicating with the passageway 21. A restriction 21' is provided in the passageway 21 and a metering pin 22' may be employed for varying the size of the passage therethrough. The tubular member 22 is provided with a lateral nozzle or discharge jet 24 substantially 85 axial with the carbureting chamber 10 and projecting into the constricted portion of the venturi 25, so as to be subject to the velocity suction of the stream of air passing through the constricted portion of said 90 venturi. The tubular member 22 extends beyond one side of the chamber 10 and receives an adjustable air jet 26 in the form of a metering screw having a constricted bore 27 therein. The screw is provided with a head 95 28 and is threaded into the end of the tube. A passageway 29 for air only extends from the tube 21 to a point 30 on the engine side of the throttle 13. It will be noted that communication between the passageway 29 100 and the tubular nozzle 22 is controlled by the adjustable air jet 26. The passageway 29 may be adapted for controlling the air bleed and impact action of the air jet 27 on the nozzle 22, or this passageway may function to supply an idling mixture to the carburetor, as I shall presently describe.

The main air inlet is controlled by a

poppet valve 31, the air inlet being provided with a seat 32 to receive said valve when closed. The seat 32 is carried by a head 33 forming a cylinder 34, the stem 35 of said valve 31 having a piston 36 thereon adapted to move in said cylinder. The upper end of the cylinder is closed by a cap 37 and a tube 38 connects the upper end of the cylinder 34 with the carbureting chamber on the engine side of the throttle, as indicated at 39. The degree of suction imposed upon the cylinder 34 and piston 36 may be regulated by a needle valve 40. A stop pin 59 engages in a groove in the piston 36 and limits its downward movement.

For idling purposes a nozzle 41 may be provided having a constricted passageway 42 therein, said nozzle being placed between the venturi and the throttle and communicating by means of a passageway 43 with the float chamber. In order that the idling jet 41 may function when the throttle is closed, a slight space 56 is provided around the throttle. Suitable headed screws 44 and 45 are provided below the nozzles 22 and 41 to permit cleaning when necessary.

The fuel raising feature of the invention includes an auxiliary tank 46, the bottom 45' of which serves as a cover for the constant level chamber 16. As shown the tank 46 is formed of sheet metal and engages over the upper margin of the chamber 16 forming an airtight connection. The tank is made of sheet metal for the sake of lightness. The tank 46 contains a float 47 controlling a valve 48, said float being pivoted at 49 on the wall of the tank. The valve 48 controls a conduit 50 which extends to the main supply tank 50' generally located below the level of the carburetor.

Suction is applied to both the constant level chamber 16 and the supplementary tank 46 by a conduit 51 connecting at 52 with the carbureting chamber ahead of the Venturi tube 25. The purpose of this will appear presently. The conduit 51 extends upwardly through the chamber 16 and auxiliary tank 46, having communication at 53 with the chamber 16 above the level of liquid therein. A needle valve 55 regulates the amount of atmospheric pressure admitted to the top of the tank 46.

A suitable needle valve 57 may be provided for regulating the degree of atmospheric pressure admitted to the constant level chamber 16. The ports 53 and 54 may, if desired, be suitably proportioned to maintain different degrees of suction in the upper and lower fuel chambers, or this may be accomplished by the relatively adjustable vent valves 55 and 57.

The operation of this form of my invention is as follows:

At closed throttle running, the secondary or idling nozzle is discharging fuel, this

nozzle projecting to a point just below the center of the air stream from the venturi, and just beyond the venturi, so that there will be at closed throttle sufficient velocity of air to overcome capillary action and the 70 constricted nature of the bore in said nozzle. The constricted bore 42 and the relatively low suction at the nozzle 41 at open throttle prevents fuel discharging in any appreciable quantity from said nozzle at that time. 75

At closed throttle, suction is greater on the engine side thereof with the result that the valve 31 is maintained practically closed in response to the action of suction on the piston 36. The position of this anterior air valve can be determined for any given manifold suction by properly proportioning the respective areas of the piston 36 and the upper face of valve 31. During this closed throttle running, air from an additional source may be made to enter the carbureting chamber through the screw 26 to assist in the functioning of the idling jet. By screwing down this air jet screw to sufficiently restrict or entirely close the passageway 29 the influence of this passageway on the air jet is restricted or eliminated. Then substantially all the air entering the air jet 27 is discharged into the nozzle bore 22 and through the nozzle 24. By screwing this air jet upwardly to place its tip under the influence of the passageway 29 another range of conditions may be taken care of. 90

The high suction in the passageway 29 at restricted throttle may be employed to withdraw part of the air entering through the air jet 27 by screwing the same upwardly, whereby the air issuing from the nozzle 24 may be reduced or eliminated. By properly proportioning the passages 29 and adjusting 105 the jet to the correct height, relative to the intersection with the passageway 29, the high suction prevailing in the passageway 29 at restricted throttle may be utilized to withdraw all the air entering through the air jet and in addition to create a suction in the bore of the nozzle tube 22. This suction when added to that in the carbureting chamber may become sufficient to cause fuel to rise in the passageway 22 up to the nozzle 24 and a discharge of fuel from the nozzle 24 during this restricted throttle where- 110

by the nozzle will then function as an idling jet. During this restricted throttle running the suction on the engine side of the throttle is usually greater than in the constricted part of the venturi. The suction in the float chamber 16 co-operates with the preceding arrangement of air jet owing to the fact that by reason of this back suction in the float chamber a relatively small amount of air admitted at the air jet is sufficient to overcome any head of fuel. It will thus be seen that by a simple adjustment of this air jet screw a wide range of conditions may be 115 120 125 130

taken care of, as by causing a discharge of air from the nozzle 24 or a discharge of fuel. In addition this air jet affords an economizing means or a means for preventing overenriching of the mixture at certain speeds, as I shall presently describe.

As the throttle is opened, the idling jet 41 begins to fall off, but not until after the main jet 24 has come into play. Thus, there is no time during the period of acceleration when pure air can reach the engine and cause loss of power. Simultaneously with opening of the throttle, the suction on the engine side thereof is communicated to the air valve 31 and the suction above the piston 36 is reduced resulting in a partial opening of the valve. This valve opens against the suction in the cylinder 33, and is therefore largely governed by the piston, the movement of this valve being somewhat damped thereby, which is beneficial in preventing fluttering of the same.

When the air jet is adjusted to place a certain proportion of the passageway 29 in communication with the jet tip it will be apparent that air entering the jet is largely drawn past the throttle through the passageway 29, and it is only when the suction of the venturi is greater than that at the opening 30, that air flows down into the main nozzle. Such conditions prevail ordinarily at the higher speeds, and it is at these speeds that it is desirable to prevent over-enriching of the mixture, or to effect an economizing operation. This is accomplished by the air jet which bleeds air into the nozzle bore to partially satisfy the suction at the throat of the venturi and to dilute and atomize the fuel. The location of this air jet relative to the point of entrance of the fuel affords a noteworthy action in that the size of the jet orifice results in a relatively high velocity of the air entering therethrough and the impact or impingement of this high velocity air on the fuel in a direction counter to the flow of the fuel deters the flow. This provides a further economizing action and such fuel as is discharged is nebulized to a certain extent by the impingement of the air.

The ability of the carburetor to lift fuel from a supply tank depends upon the suction available for this purpose. The provision of the anterior air valve 31 responsive partly to manifold suction, assists in maintaining a certain degree of suction in the carbureting chamber at practically all engine speeds for performing the fuel lifting operation. While this suction may vary widely at different speeds and throttle positions the air valve 31 maintains a sufficiently high suction in the carbureting chamber to lift fuel throughout the normal range of speeds and running conditions. It will be seen that suction is communicated through the conduit 51 to the float chamber 16 and

tank 46. As the tank 46 fills, after having filled the float chamber, the float 47 will close communication to the conduit 50. It will be apparent that some time must elapse before the carburetor would run dry even though the suction in the carbureting chamber should be killed, or should fall so low as to be incapable of lifting fuel, owing to the fact that a reserve supply of fuel is kept in the tank 46 and only when the level falls below the predetermined amount in the constant level chamber is the supply in the tank 46 drawn upon. The difference of pressure which causes discharge of fuel from the nozzles in the carbureting chamber follows from the velocity suction of the air rushing past the nozzles, this velocity suction being in excess of the static suction in the carbureting chamber. The admission of atmosphere through the vent valves 55 and 57 may also be employed to produce different feeding pressures.

In Fig. 3 I have shown the arrangement of the air jet 26 and the passageway 29 slightly modified with the view to causing the idling discharge of fuel to pass through the passageway 29. In this arrangement the discharge port 30 is located to be intersected by the lip of the throttle 13 when the same is in its idling position. The static suction of the manifold together with the high velocity flow of air through the port 30 around the throttle produces a relatively high suction in the passageway 29 which draws an idling discharge of fuel from the bore of the nozzle tube 22 up past the air jet 26 and through the passageway 29 and out through the port 30. The air admitted to the fuel stream through the air jet 26 and nozzle 24 assists in atomizing the fuel and proportioning this idling mixture. When the throttle is opened the suction in the passageway 29 drops off and thereafter the air entering through the air jet and passageway 29 may be utilized for controlling the fuel discharge from the nozzle 24, as hereinbefore described. It is not essential for this idling operation that the port 30 intersect the lip of the throttle when in idling position, as the port may be positioned as shown in Fig. 1 if desired.

In the modified embodiments shown in Figs. 4, 5 and 6 the general structure is substantially the same as the preceding form and the same reference numerals with the addition of a prime have been applied to corresponding parts. In this form the suction prevailing in the carbureting chamber is conducted to the carburetor float chamber 16' and the supplementary tank 46' thru separate conduits 61 and 62. The conduit 61 leads from the carbureting chamber at a point posterior to the venturi 25' and the conduit 62 leads from the carbureting chamber at a point anterior to the Venturi tube. The conduit 62 communicates with the car-

bureting chamber through a threaded boss 63 into which screws an adjusting screw 64 by the manipulation of which the effective area of the conduit 62 can be controlled.

5 A priming or choking valve 65 is interposed in the carbureting chamber between the anterior air valve 31' and the fuel nozzle 24'.

The choke valve 65 is located to intersect the suction connection 62 so that when the 10 choke valve is closed this connection will be subjected to the relatively high suction posterior to the choke valve and also to the relatively low suction anterior to the choke valve.

15 The combination of the two suctions is of less degree than the suction transmitted through the conduit 61, and "bleeds" or partially satisfies this higher suction. Hence the pressure prevailing in the carburetor float chamber 16' is sufficiently higher than 20 at the carburetor nozzle 24' to insure the proper flow of fuel when the choke is restricted. The shaft 66 upon which this choker valve is mounted is adapted to have suitable connection with a dash or steering 25 post control through the arm 67 and any other suitable connecting member.

From the float chamber 16' the fuel enters an accelerating well 68 which is preferably cast integral with the body of the carburetor 30 within the float chamber. The entrance to this accelerating well is through a plug 69 having a calibrated orifice, this plug being removable for easy substitution by plugs having larger or smaller orifices. From the well 68 the fuel is conducted through a passageway 71 into a well or chamber 72. An adjustable needle valve 73 may be provided for controlling the rate of discharge from the well 68. The nozzle tube 74 is extended 35 downwardly from the top of the carbureting chamber to thread into the chamber 72. A raised rib 75 is cast integrally with the carbureting chamber to extend longitudinally thereof along the upper part of the 40 chamber, and the nozzle tube 74 is passed down through a lateral extension 75' from this rib, a cap 76 on the end of the tube closing off the bore extending down through the enlargement 75'. An inner tube 77 is mounted 45 in the nozzle tube 74 by a threaded enlargement 78 which screws into threads in the interior of the nozzle tube 74 above the level of the main nozzle 24'. This inner tube is spaced from the inner walls of the 50 nozzle tube 74 to permit free passage of fuel to the main nozzle 24' when such nozzle is in operation. This inner tube 77 serves to conduct the necessary fuel for the idling 55 operation of the engine to the upper end of the nozzle tube 74 where it is atomized and diluted by air entering through a port 79 in the rear wall of the nozzle tube 74. The port 79 is positioned to discharge across or up around the discharge end of the inner 60 tube 77 for securing the most effective atom-

ization of the fuel. The resulting mixture is conducted laterally from the upper end of the nozzle tube through a passageway 81 and into a longitudinal passageway 82 which extends centrally through the rib 75. An 70 adjustable needle valve 83 is preferably provided for controlling the volume of air and the quantity of mixture admitted to the passageway 82. The forward end of the passageway 82 opens into the mixture outlet thru an idling port or jet 84 which is located on the engine side of the throttle 13. 75

The vacuum chamber 34' which controls the anterior air valve 31' may have connection with the engine side of the throttle 80 valve 13 through an arrangement of tube or conduit as described in the previous embodiment, or it may communicate with the passageway 82. This latter arrangement is illustrated in Fig. 6 wherein it will be noted 85 that the passageway 82 is extended up through the supporting structure 33' of the cylinder by way of a diagonal and upwardly extending passageway 82'.

In this embodiment the float 16 and the 90 supplementary tank 46' are both within the confines of a chamber 85 which may cast integral with the body of the carburetor. A removal cover 86 closes the top of the chamber 85. The supplementary tank 95 proper, which is designated 46', is constructed as a sheet metal container spaced from the walls of the chamber 85. This supplementary tank may be supported from the cover 86 for removal therewith, or may 100 be removably supported in the chamber 85 in any suitable manner. The upper float 47' controls a suitable valve 48' which governs the admission of fuel to the supplementary tank. The float is suitably pivoted 105 to a stationary lug 49' and preferably has a projecting tail to limit the downward movement of the float. The lower float 17' is pivotally supported upon a lug 18' carried on the bottom of the supplementary tank 46', this float controlling a suitable valve 19' in the bottom of the supplementary tank and having a suitable tail or the like to limit its downward motion. The suction 110 which is communicated to the chamber 85 through the conduits 61 and 62 has communication with the interior of the supplementary tank 46' through holes 88 at the upper end of the tank. A vent valve 55' 115 may be provided for venting a restricted amount of atmosphere into the chamber 85, if desired.

In operation the anterior air valve 31' operates to maintain a certain degree of suction in the carbureting chamber for performing the fuel lifting operation. In idling a certain volume of the restricted amount of air admitted by the valve 31' enters through the port 79 under high velocity and draws fuel from the upper 120

end of the inner idling tube 77 under the suction prevailing in the passageway 82. The resultant mixture is projected through passageway 81 under the control of the 5 needle valve 83, and flows into the passageway 82 and into the intake manifold through the idling port 84. The main nozzle 24' comes into operation when the throttle 13 is opened by drawing fuel upwardly around the inner idling tube 77 under the relatively high velocity suction existing at the throat of the Venturi tube 25'. A sudden acceleration will draw fuel from the accelerating well 68 faster than it enters 10 through the plug 69 so that the level in the accelerating well will be temporarily lowered. While the plug 69 may calibrate the flow to the end of the most desirable economy it will be noted that the well 68 15 affords the reserve accumulation for suddenly enriching the mixture upon acceleration.

The proper proportioning of the mixture through all changes in engine speed is materially assisted by the provision of the two suction conduits 61 and 62. One conduit transmits to the float chamber the suction posterior to the venturi 25' and the other conduit the suction anterior to the venturi. 20 The suction at these two points are different owing to the constriction interposed by the venturi. The size of this venturi may be determined for obtaining any desired difference of suction between these two points for a given engine speed. This difference of 25 suction does not remain constant but varies through a considerable range with the variations in engine speed, owing particularly to the chocking action of the venturi at high engine speeds. Consequently for one engine speed the differential suction, which the two conduits 61 and 62 transmit to the float chamber, will be of one value and for another engine speed this differential suction 30 will be of another value. Thus the rate of fuel flow from the carbureting chamber is effectively proportioned by these differential suctions. The differential relation between the two suctions transmitted through the conduits 61 and 62 may be proportioned in any desired ratio by the adjustment of the thumb-screw 64 which restricts or enlarges the conduit 62.

I claim:

1. In a carburetor, a carbureting chamber 55 having an air inlet and a mixture outlet, a throttle valve in said mixture outlet, a main fuel nozzle discharging into said carbureting chamber, a passageway extending from said nozzle and terminating in said 60 mixture outlet outside of said throttle, and air bleed means open at all times to said nozzle and being adjustable to control the connection of said passageway with said nozzle and said air bleed means. 65

2. In a carburetor, a carbureting chamber having an air inlet and a mixture outlet, a throttle valve in said mixture outlet, a fuel supply pipe in said carbureting chamber, a main fuel nozzle discharging into said 70 carbureting chamber from said supply pipe, a passageway extending from said supply pipe to the mixture outlet outside of said throttle valve, and air bleeding mechanism connected with said supply pipe and passageway, said air bleeding mechanism being always open to said supply pipe and being adjustable to permit the engine suction to be effective through said passageway to raise fuel in said supply pipe to the nozzle 80 during restricted throttle position whereby said nozzle may act as an idling nozzle. 75

3. In a carburetor, a carbureting chamber having an air inlet and a mixture outlet, a throttle valve in said mixture outlet, a fuel supply pipe in said carbureting chamber, a main fuel nozzle connecting with said supply pipe above the normal fuel level 85 therein and being adapted to discharge into said mixture outlet, a passageway connecting with said supply pipe above the connection of the nozzle therewith and terminating in said mixture outlet adjacent to said throttle valve, whereby said passageway and said nozzle will be subjected to the suction of the engine, and air bleed mechanism permanently open to the supply pipe and adjustable to adapt either said nozzle or said passageway for supplying idling mixture when said 90 throttle is in idling position, said bleeding mechanism acting to bleed air into the fuel when said passageway is supplying idling mixture. 95 100

In witness whereof, I hereunto subscribe my name this 14th day of February, 1922.

NOBLE ECKLES.
